Attorney

UNITED STATES PATENT OFFICE.

BAYARD E. RICHARDSON, OF GRAND RAPIDS, MICHIGAN.

DESK TOP.

Application filed December 13, 1926. Serial No. 154,560.

This invention relates to a top for desks, tables, or other articles of furniture which make use of a horizontal top, and the invention is particularly concerned with the construction of a novel top wherein the core, which heretofore usually has been of wood strengthened and reinforced by cross bands of veneer, is replaced by a cementitious composition impervious to and insoluble in water and to which finishing veneers may be applied at its upper and lower sides and border bands at its edges, the same being readily glued thereto. This makes a light, strong, durable and inexpensive top to manufacture and one which, by reason of the material used, is very easily manufactured, there being no warping by reason of the core swelling and shrinking as has previously been the case with wood cores which take up water easily and many of the difficulties and troubles hereinbefore considered impossible to eliminate, are eliminated with the construction of top which I have devised.

For an understanding of the invention reference may be had to the following description taken in connection with the accompanying drawing, in which,

Fig. 1 is a perspective view of the inner core used with the top of my invention. Fig. 2 is a fragmentary perspective view of one corner of the top after the core has had the border bands and the upper and lower veneers attached thereto, and

Fig. 3 is an enlarged fragmentary vertical section through one side of the construction shown in Fig. 2.

Like reference characters refer to like parts in the different figures of the drawing.

The core is a composition of magnesium oxychloride throughout which particles of cork of varying sizes are distributed. The magnesium oxychloride is made by mixing magnesium oxide and magnesium chloride in solution and working the cork into the plastic mass which eventually sets and hardens, being placed in a mould so that a plate or slab such as indicated at 1, of substantially the required dimensions for a table, desk or other top, is produced throughout which the cork, indicated at 2, is disseminated. The particles of cork may be of very big sizes, there being no necessity of screening or maintaining the cork particles to any one size. The cork used may be as much as fifty per cent of the total bulk of

the slab 1 made. When the magnesium oxide and magnesium chloride react to produce the magnesium oxychloride all of the water which has been used is absorbed as water of crystallization in the reaction and the magnesium oxychloride produced is thereafter not acted upon by water, does not absorb it and does not dissolve in the presence of water. The cork, of course, is substantially impervious to the penetration of water as is well known.

After the slab thus described has been produced the edges are trimmed by any suitable cutting device such as a saw or plane and if necessary the upper and lower sides of the slab are planed or otherwise finished so that they will be parallel. The oxychloride impregnated with cork is very easily worked without detriment to the tools used and can be finished to any desired size. The edge bands or border strips 3 are glued to the edges of the slab, use being made of casein glue. Then both sides are surfaced, that is sanded down or otherwise machined so as to make absolutely smooth parallel upper and lower surfaces. After this is done the veneers indicated at 4 are applied. Two layers of veneer are shown at each side and in practice the inner veneer may be of a more expensive type and one capable of taking a high finish, such as mahogany, oak, walnut and the like.

This completes the top except for the necessary sanding, staining, varnishing and the other finishing operations which form no part of the present invention.

This construction of table top has proved very satisfactory. The magnesium oxychloride and cork are relatively inexpensive and the core of slab 1 produced is light, strong and durable and is particularly effective in that its freedom from water absorption precludes any warping or twisting of the top during either the manufacture of the core or the manufacture of the finished top. Moreover the consumption of wood in the manufacture of the top is greatly reduced inasmuch as the core which forms a very large proportion of the top is wholly replaced by the composition described. The invention is defined in the appended claims and is to be considered comprehensive of all forms of structure coming within their scope.

I claim:

1. A top of the class described comprising,

a core of cementitious material disseminated throughout which are pieces of cork, wood bands glued to the edges of the core, and wood veneers glued to the upper and lower sides of the core and to the upper and lower sides of the bands.

2. A top of the class described comprising, a core of uniform thickness of magnesium oxychloride, wood bands glued to the edges 10 of the core, and wood veneers glued to the upper and lower sides of said core and to the upper and lower sides of the bands.

3. A top for desks, tables and similar articles of furniture comprising, a core of uniform thickness of magnesium oxychloride, having small pieces of cork disseminated throughout the mass of the core, wood bands glued to the edges of said core, and

wood veneers glued to the upper and lower sides of the core and to the upper and lower sides of said bands.

4. A top of the class described comprising, a core of uniform thickness, of magnesium oxychloride having small pieces of cork disseminated throughout the mass of the core 25 and exposed on its surfaces, wood bands glued to each of the respective edges of said core and wood veneers glued to the upper and lower sides of the core and overlapping and glued to the upper and lower sides of 30 said bands, said glue on both the bands and the veneers adhering to the exposed pieces of cork on the surfaces of the core.

In testimony whereof I affix my signature.

BAYARD E. RICHARDSON.
